US00D794790S

(12) **United States Design Patent** (10) **Patent No.:** **US D794,790 S**
(45) **Date of Patent:** **** Aug. 15, 2017**

(54) **DISPOSABLE SAFETY LANCET**

(71) Applicant: **Sterilance Medical (Suzhou) Inc.**,
Suzhou (CN)

(72) Inventor: **Guoping Shi**, Suzhou (CN)

(73) Assignee: **Sterilance Medical (Suzhou) Inc.**,
Suzhou (CN)

(**) Term: **14 Years**

(21) Appl. No.: **29/517,625**

(22) Filed: **Feb. 13, 2015**

(30) **Foreign Application Priority Data**

Aug. 29, 2014 (CN) 2014 3 0316743

(51) **LOC (10) Cl.** **24-02**
(52) **U.S. Cl.**

(57) **CLAIM**

I claim the ornamental design for a disposable safety lancet, as shown and described.

DESCRIPTION

FIG. 1 is a front view of a disposable safety lancet showing my new design;

FIG. 2 is a rear view thereof;

FIG. 3 is a left view thereof;

FIG. 4 is a right view thereof;

FIG. 5 is a top view thereof;

FIG. 6 is a bottom view thereof;

FIG. 7 is a perspective view thereof; and,

FIG. 8 is a perspective view thereof.

The broken lines represent unclaimed portions of the claimed article and form no part of the claimed design.

1 Claim, 8 Drawing Sheets
